UNITED STATES PATENT OFFICE.

IRA A. MANN, OF PITTSBURGH, PENNSYLVANIA.

PLUMBING-FIXTURE.

1,124,049.

Specification of Letters Patent.

Patented Jan. 5, 1915.

Application filed July 23, 1913. Serial No. 731,526.

To all whom it may concern:

Be it known that I, IRA A. MANN, a citizen of the United States, residing at Pittsburgh, in the county of Allegheny and State 5 of Pennsylvania, have invented certain new and useful Improvements in Plumbing-Fixtures, of which the following is a specification.

The invention relates to plumbing fixtures 10 involving the use of wall bowls such as closets, sinks, and the like. It has for its primary objects; the provision of apparatus of simplified and cheapened construction particularly as to the supporting and outlet connection 15 between the bowl and soil or outlet pipe; the provision of a construction wherein a more secure and positive support for the bowl from the outlet piping is secured than has heretofore been possible; the provision 20 of a construction in which a water seal is provided for the inner end of the horizontal connection from the soil or outlet pipe and the bowl; and the provision of a construction particularly adapted for use in connection 25 with a peripheral washout jet. Certain embodiments of the invention are illustrated in the accompanying drawings wherein—

Fig. 1 is a vertical section through the preferred form of my invention as applied 30 to a closet. Fig. 2 is a side elevation of the construction of Fig. 1. Fig. 3 is a plan view of the bearing plate employed in the constructions of Figs. 1 and 2. Fig. 4 is a side elevation of the coupling or sleeve, Fig. 5 is 35 a side elevation of a modified form of sleeve employed with a siphon closet where the long leg of the siphon is placed behind the wall or partition. Figs. 6 and 7 are a section and side elevation respectively through a modified form of construction. Figs. 8 and 9 40 are details of the structure shown in Figs. 6 and 7, Fig. 8 being an enlarged section through the hinge connection, and Fig. 9 being a face view of the securing plate employed. Fig. 10 is a section through a modified construction. Fig. 11 is a plan view of the supporting means of the structure of Fig. 10, with the bowl removed. Fig. 12 is a front view of the structure shown in Fig. 11, 45 Fig. 12 is a face view of the T employed in the soil pipe in the construction of Fig. 10. Fig. 14 is a section through a modification differing slightly from that of Figs. 1 and 2. Figs. 15 and 16 are sectional and side ele-

vation views respectively of a modification 55 wherein the bowl is a sink, Fig. 17 is a plan view of the bracket means for securing the upper portion of the sink to the vertical piping, Fig. 18 is an elevation of the rear face of the sink removed from the wall, and Fig. 19 is a side elevation of the coupling or sleeve employed with the construction of Fig. 15.

In its preferred form the invention contemplates the support of the bowl entirely 65 from the coupling which connects the bowl with the outlet or soil pipe. I have found that this coupling is amply strong to support the entire weight of the bowl, and the elimination of other supporting means materially cheapens and simplifies the construction, and involves a considerable saving of space. The construction of course involves the movement of the bowl with the soil or outlet pipe in its expansion and contraction 70 due to changes of temperature, and to provide for such movement I preferably embed a bearing plate in the face of the wall against which the bearing face of the closet engages, sufficient space being provided 75 around the coupling in order to permit of any desired range of movement of the bowl vertically and laterally. I also preferably extend the coupling sleeve a considerable distance to the front of the wall and incline 80 it downwardly so as to fit the outlet passage of the bowl. This serves the two functions of giving a large bearing area on the coupling upon which to support the bowl, and of providing a joint between the lower 85 end of the coupling sleeve and the bowl below the surface of the water in the bowl, so that a water seal is provided, thus making it certain that no sewer gas can leak through the joint into the house. The construction 90 is illustrated for the most part as applied to closets, but it will be understood that the invention is applicable to any receptacle which is supported from the wall, such as sinks and the like, and the term "bowl" is 95 used throughout in its generic sense to refer to any such receptacle supported from the wall and discharging through a soil or outlet pipe in the partition.

Referring first to the construction shown 100 in Figs. 1 to 4, 1 is the bowl which may be of any approved type; 2 is the seat secured by the hinge members 3 and 4; 5 is the soil

or outlet pipe of which the T 6 constitutes a part; 7 is a bearing plate of metal set into the front face of the partition 8; and 9 is a coupling or sleeve which takes the entire 5 weight of the bowl and serves to secure such bowl to the T 6.

The upper end of the coupling or sleeve 9 is screw threaded into the T as indicated at 10, and the joint is made tight and the sleeve 10 prevented from rotating in the T, by means of the packing 11, preferably metallic, which is tamped tightly into the recess in the front face of the T surrounding the sleeve.

Compressible gaskets 12 and 13 of rubber 15 or similar material are provided at the shoulder 14 and at the front end of the sleeve, respectively. The bowl is pulled longitudinally of the sleeve in order to compress the gaskets 12 and 13 and make tight 20 joints, by means of the bolts 15 on opposite sides of the bowl. These bolts engage at their front ends the abutments 16 carried by the bowl (Fig. 2), and at their other ends pass through openings in lugs 17 integral 25 with the sleeves 9. Secured between the heads 18 of the bolts 15 (Fig. 1) and the lugs 17 are the seat hinge supporting brackets 19. The hinge members 1 are secured to these brackets 19 by means of the 30 bolts 20. The bolts 15 therefore perform the double function of clamping the bowl to the sleeve 9, and of securing the seat hinge supporting bracket 19. The annular space between the sleeve 9 and the bowl, and 35 lying between the gaskets 12 and 13, is preferably filled with an elastic cement in order to provide an extensive bearing surface between the sleeve and the bowl, such extended bearing surface being desirable 40 since the sleeve 9 supports the entire weight of the bowl.

Inasmuch as the bowl is supported entirely upon the outlet pipe 5, provision must be made to permit the sleeve 9 and the bowl 45 to move vertically with the expansion and contraction of the soil pipe. To this end the bearing plate 7 which surrounds the sleeve or coupling 9 is provided with an opening 21 of such size that the coupling is free to 50 work up and down therein and also laterally a slight amount. The plate 7 prevents injury and gives a bearing over which the face of the bowl may ride freely as the bowl follows the movements of the supporting 55 outlet piping.

Adjacent the lower end of the sleeve 9 an annular recess 22 is provided in the bowl, which recess 22 is connected with the water supply for flushing the bowl, such water 60 supply also having connection with the annular ring 23 at the upper edge of the bowl, in the usual manner. The lower end of the sleeve 9 partially fills the outlet from the recess 22, thus providing for an annular 65 flushing jet which discharges along the pe-

riphery of the sleeve 9. The sleeve 9 is preferably made of cast iron, and is fitted at its lower end with a sleeve 24 of relatively soft non-corrodible metal such as brass. By filing the lower edge of this ring or sleeve 70 24, the size of the jet opening may be regulated to suit the requirements. The extreme end of the sleeve 9 is preferably inclined where it bears against the gasket 13, so as to give a wedging action and a tighter joint 75 at this point. If desired, openings 25 may be provided through the vitreous lip adjacent the annular jet, so that in the operation of the closet oblique jets of water are forced into the body of water lying within the 80 sleeve 9.

In installing the closet the sleeve 9 is screwthreaded into the T 6 to such a point that when the bolts 15 are drawn tight the bearing face of the closet will engage, or 85 approximately engage, the bearing plate 7, and after such adjustment, and before the bowl is finally secured in position by the bolts 15, the metallic packing 11 is tamped into position, thus serving to make a tight 90 joint between the sleeve and the T, and preventing any rotation of the sleeve upon its screwthreaded connection with the T. An absolutely tight joint between the sleeve and the bowl is insured by reason of the 95 gaskets 12 and 13, and the joint is further guarded against the passage of sewer gas from the soil pipe, by reason of the fact that the gasket 13 lies below the water level A of the bowl. A water seal is thus provided for one end of the coupling or sleeve, and even though there should be a leakage of water past the joint there can be no leakage of sewer gas.

The utilizing of the end of the sleeve 9 105 as one side of the peripheral jet passage is of advantage for two reasons. In the first place this arrangement permits of the adjustment of the size of the peripheral jet to suit requirements, which is more or less important, and in the second place the danger of the annular space being filled with the gloss employed in coating the bowl is avoided. Difficulty is ordinarily experienced in the glazing operation, by reason of the collection of gloss in relatively narrow passages, and this difficulty is entirely eliminated, since the lower edge of the sleeve opposing the vitreous glazed lip is adjusted to suit requirements, after the glazing operation. 110 The arrangement also permits the centerline of the soil pipe to be positioned at a minimum distance from the bearing face of the bowl, thus reducing the thickness of the partition required for the soil pipe, and also permits the depth of the bowl 115 to be reduced to a minimum.

Where a siphon jet closet is to be employed, such as that illustrated in my Patent No. 1,017,437, issued February 13, 1912, 120

the type of sleeve 9' as illustrated in Fig. 5 may be employed, such sleeve being integral with the long leg 26 of the siphon lying behind the partition. This leg 26 is of course secured to the soil pipe.

In the construction of Figs. 6 to 9, the parts 1², 2², 3², 4², 5², 6², and 9² correspond to the parts 1, 2, 3, 4, 5, 6, and 9, in the construction of Figs. 1 and 2, but the means for securing the sleeve with respect to the bowl is modified, as is also the means for securing the hinges of the seat. The sleeve is provided with a shoulder 27, and this shoulder is engaged by a plate 28 shown in detail in Fig. 9 and provided with the bolt holes 29. The bowl is provided with a shelf 30 opposing the plate 28 and secured thereto by means of the hollow bolts 31 (Fig. 8). The bolts serve to tighten the sleeve 9² with respect to the gaskets which are arranged as in the construction of Figs. 1 and 2. In order to give additional support to the bowl a yoke 32 engages the piping above the T 6² attachment to the bowl being secured by means of the bolts 33 which extend through the hinge members 4² and through the below bolts 31 as indicated in Fig. 8. In order to permit of the tamping of the packing material 11² after the plate 28 is in position the slots 35 are provided in the plate 28 (Fig. 9) through which a tamping tool may be inserted. The lower securing bolts 31 which do not have hinge securing bolts extending therethrough do not of course need to be made hollow.

Figs. 10 to 13 illustrate another modified form of structure which may be employed where bowls are supported on opposite sides of a partition. In this construction a double T 6² is employed together with two securing yokes formed by the rods 36, 37, and 38. The rod 37 passes through the fitting and has hooked around it the ends of the rods 38 and 36 as indicated at 39 and 40. The right hand ends of the rods 38 and 37 extend through lugs 41 and 42 carried by the sleeve 9², and are screw threaded to blocks 43 in which the hinge rod 44 is swiveled. This hinge rod also passes through another lug 45 carried by the sleeve 9². The ends of the hinge rod 44 carry the hinge members 4². Lock nuts 46 carried by the rods 36 and 37 bear against the flange of the T. The bolts 47 serve to clamp the sleeve to the bowl, the upper ends thereof extending through slots 48 (Fig. 13) in the flange of the fitting 6², and the heads 49 of the bolts lying in recesses in such flange as indicated in Fig. 10. The parts 1², 2² and 22² correspond to the parts 1, 2, and 22 in Fig. 1, and means for securing the tight joint between the sleeve and the bowl are the same as heretofore described in connection with Fig. 1.

Fig. 14 illustrates a departure from the

construction of Figs. 1 and 2 in that the peripheral jet is omitted and a center jet 49 substituted therefor. The lower end of the sleeve 9² opposes a shoulder 50, and packing gaskets are employed as in the construction of Fig. 1. The seat 2⁴ is hinged as in the construction of Fig. 1, and the other parts of the construction are the same throughout as heretofore described in with Fig. 1.

Figs. 15 to 19 illustrate the application of the invention to a basin. This basin 1² may be of any approved type, and its weight is supported from the piping 5², so that the entire weight of the device is removed from the partition. The outlet coupling or sleeve 9² bears at its lower end upon a gasket 13², and its upper portion is provided with a flange 14² which bears upon another gasket 12². The upper end of the sleeve is screw threaded to the T 6² as heretofore described, and the basin is clamped longitudinally of the bowl to compress the gaskets, by means of the bolts 15², such bolts extending at their lower ends through the abutments 16² carried by the basin, and at their upper ends through lugs 51 integral with the T 6². As an additional support the bolts 52 are employed (Fig. 15) such bolts being screwed into the arms 53 slidably mounted upon the bracket 54 (Fig. 17). The bracket 54 is secured to the piping by means of the yoke 55 held in position by the bolts as illustrated in Fig. 17. The bowl is provided with slots 56 for the bolts 52 (Fig. 18) in order to permit of a slight vertical movement of the basin in case such movement is required by the expansion and contraction of the piping 5².

What I claim is:

1. The combination in a wall bowl plumbing fixture, a vertical outlet pipe, a rigid supporting coupling projecting laterally therefrom, a bearing plate secured to the front of the wall, a bowl supported upon the coupling and having a bearing face opposing the said bearing plate, the said bowl being free to move vertically over the bearing plate as the vertical pipe expands and contracts and moves the bowl up and down.

2. The combination with a wall bowl having an upwardly-directed inclined outlet passage leading from its lower portion, and an annular jet passageway surrounding the lower end of the passage, an outlet pipe at the rear of the bowl, a supporting metal outlet coupling secured rigidly at one end to the outlet pipe and having its other end inclined downwardly into the said passage and having its lower end partially closing the said annular jet passageway, and means for holding the bowl against longitudinal movement on the outlet coupling.

3. The combination in a wall bowl plumbing fixture, piping comprising a vertical

- outlet pipe, and a supporting coupling projecting substantially horizontally therefrom and inclined downward, a bowl having an upwardly inclined outlet passage telescoping over the downwardly inclined end of the coupling, whereby the coupling acts as an internal bearing support for the bowl, securing means for drawing the bowl longitudinally of the coupling, and tension means between coupling and bowl above and to the rear of the lower end of the coupling, adapted to apply stress at substantially right angles to the axis of the inclined portion of the coupling.
4. The combination in a wall bowl plumbing fixture, piping comprising a vertical outlet pipe, and a supporting coupling projecting therefrom and having its outer end inclined downwardly, a bowl having an upwardly inclined outlet passage telescoping over the inclined portion of the coupling, a shelf at the upper rear portion of the bowl, upwardly extending bracket means rigid with the coupling and opposing the said shelf, and tension means transverse to the axis of the inclined portion of the

coupling and extending between the shelf and the bracket means.

5. The combination in a wall bowl plumbing fixture, piping comprising a vertical outlet pipe, and a rigid supporting coupling projecting substantially horizontally therefrom and then inclined downward at an angle of approximately 40° to the horizontal, a bowl having an upwardly inclined outlet passage telescoping over the downwardly inclined end of the coupling, and securing means for drawing the bowl longitudinally of the coupling, the said coupling taking substantially the entire weight of the bowl and the inclined portion of the coupling constituting the lining of the outlet passage of the bowl, and the upper outer surface hereof taking the downward thrust of the bowl.

In testimony whereof I have hereunto signed my name in the presence of the two subscribed witnesses.
